UNITED STATES PATENT OFFICE.

HERMANN CHRISTIAN FISCHER, OF VIENNA, AUSTRIA, ASSIGNOR TO THE FIRM:
DURKOPPWERKE AKTIEN-GESELLSCHAFT, OF BIELEFIELD, GERMANY.

MACHINE FOR DRAWING OUT THREADS FROM TISSUES.

Application filed February 8, 1926, Serial No. 86,910, and in Germany January 15, 1925.

Machines for drawing-out threads from tissues are known heretofore, in which an up and down movable draw-out needle co-acts in such a way with a cut-off device arranged underneath the same that the threads drawn-out from the tissue are cut-off. Said known machines have the drawback that they do not work reliably and that they cannot be used for all kinds of tissues, because the tissue was not satisfactorily stretched in dependence upon the working of the cutter.

To overcome said drawback, according to the present invention, besides the pressure-feet forcing the tissue against the feed contrivance, a separate pressure-foot is arranged, which co-acts independently from said pressure-feet with the counter-cutter, while means are provided for controlling the counter-cutter and said pressure-foot in such a way that they are approached to one another at the moment of cutting whereby an increased stretching of the tissue is attained.

The accompanying drawings illustrate the improved arrangement:

Figs. 1 and 2 are respectively a front view and a side view of a machine fitted therewith,

Fig. 3 is a side view of the cutter casing,

Figs. 4 and 5 are respectively a longitudinal section through and an elevation of the mounting of the cutter shaft in the cutter casing,

Fig. 6 is a sectional detail of Fig. 1 showing the arrangement of the pressure-feet,

Fig. 7 is a plan view of the cutters, and

Fig. 8 shows the control for the separate pressure-foot.

The head 1 of the machine frame 2 carries the up and down movable needle-bar 3 in a way known in the art, the draw-out needle 4 being fixed to the lower end of said bar. Driving is effected from the wheel 5 by the shaft 6. By a suitable transmission-gear, the shaft 6 drives by means of the feed-wheel 7 the toothed-wheels 8 and 9 which are in gear with the toothed-wheels

10 and 11 of the feed-wheels 12 and 13 for the advance of the tissue. Pressure-feet 15 arranged on the pressure-bar 14 and up and down movable by means of the latter, serve for pressing the tissue against the feed-wheels 12, 13, the pressure-feet heads 16 being in yielding contact with said feed-wheels. Between the feed-wheels 12, 13 and on guide-bars 17 a casing 18 is slideable in vertical direction (Fig. 3). In the open top end of said casing a counter-cutter 19 is yieldingly mounted and fitted with guide-arms 19^b laterally bounding the cutting-edge 19^a (Fig. 7), while on a shaft 20 a crank-arm 21 is fixed, which projects into said casing and the outer end of which serves for the reception of the cutter 22 (Fig. 2). At its underside the casing 18 bears yieldingly upon a buffer-bolt 24 arranged in the bracket 23 which carries the guide-bars 17, said bolt being so acted upon by an eccentric 26 (Figs. 1 and 2) driven from the driving-gear by means of a connection-rod 25, that the casing is yieldingly lifted at the moment of the cutting of the thread presented by the needle 4. The counter-cutter 19 is of a suitable arched formation corresponding to the casing 18 and so arranged that the cutter 22, which bears from below against the counter-cutter 19, lifts the same in such a way that the highest stretching of the tissue takes place at the cutting place. To ensure a reliable engagement between the two cutters 19 and 22, the cutter 22 is at its front end fitted with guide-pieces 27 (Fig. 7).

Above the counter-cutter 19 and on a guide-bar 28 in the machine head 1, a pressure-foot 29 is arranged, the lower end thereof being divided into two arms 30, which are rearwardly directed and located to engage in the spaces laterally of the needle 4 between counter-cutter 19 and feed-wheels 12, 13 (Figs. 1, 2 and 6) and which at their lower ends are wedge-shaped, the inner faces of said ends engaging over the counter-cutter 19. The pressure-foot 29 is yieldingly mounted by means of springs 31,

32 on the guide-bar 28, the tension of which springs can be adjusted to suit the nature of the tissue treated. A control lever 33 engaging loosely between said springs, 5 serves to move the pressure-foot 29 by means of a cam-groove 34 in a control-cam 35 keyed on the shaft 6 (Fig. 8) in such a way that with lowered needle the pressure-foot 29 bears yieldingly upon the counter- 10 cutter 19, while at the moment of cutting the spring 32 is tensioned by downward movement of the control lever 33 and thus the pressure of the pressure-foot 29 upon the counter-cutter 19 is increased, whereas 15 after completed cutting the pressure-foot 29 is slightly raised from the counter-cutter 19 by the upward movement of the control lever 33 and consequent tensioning of the spring 31, so that the further feed of the 20 tissue can unobstructedly take place.

To permit always an exact adjustment of the cutter and a variation of the stretching height of the counter-cutter, the cutter shaft 20 is mounted in a sleeve 36 (Figs. 4 and 5), 25 which is loosely arranged in another sleeve 37 and secured therein against axial displacement, while it is pressed by means of springs 38, 38 against oppositely directed wedge faces 39, 40 of screws 41 in said outer 30 sleeve 37. By adjusting said screws in the sleeve 37, the inner sleeve 36 can be exactly adjusted to its required position of height. The cutter shaft 20 is driven by articulated cranks 42, 43 (Fig. 1) of a crank-disc 44 on the lower driving-gear shaft in a way known 35 in connection with sewing machines.

After completed feed of the tissue by means of the feed-wheels 12, 13, the descending needle 4 passes through the tissue and 40 the threads are led downwards through the counter-cutter 19, the pressure-foot 29 bearing then with its arms 30 yieldingly upon the counter-cutter 19, whereby the tissue is secured in position. By the then upwardly 45 moving cutter 22 the counter-cutter 19, which is yieldingly mounted in the casing 18, is raised and thereby pressed against the oblique ends of the arms 30 of the pressure-foot 29. At the same time, the spring 32 on the guide-bar 28 of the pressure-foot 29 is 50 tensioned by the descending control lever 33 and thereby the pressure-foot 29 is also tensioned. By this co-action of the counter-cutter 19 and pressure-foot 29 and by the wedge-like action of the arms of the latter, the 55 tissue is stretched over the counter-cutter with increased pressure, so that a displacement of the tissue at the moment of cutting cannot take place. At the same time, by action of the eccentric 26 the casing is lifted, whereby 60 the elasticity is increased and an absolutely reliable cutting of the threads and guiding of the tissue is attained. After completed cutting, the pressure-foot 29 is released by retraction of the control lever 33,

while the counter-cutter moves back, so that the succeeding feed of the tissue is not impeded.

The particular advantages of the improved arrangement consist in the provision 70 of a separate pressure-foot co-acting with the counter-cutter, whereby an absolutely reliable stretching of the tissue is attained both during the passage of the needle therethrough and during the cutting of the 75 threads, while besides by reason of the arched formation of the counter-cutter the highest stretching of the tissue takes place at the moment of cutting and at the cutting place. 80

What I claim, is:

1. The combination, in a machine for drawing-out threads from tissues, of a feed-gear for advancing the tissue, pressure-feet to ensure the contact between said feed-gear and the tissue, a cut-off device comprising a cutter and a counter-cutter, a separate pressure-foot co-acting with said counter-cutter independently from said pressure-feet, and means to approach said counter-cutter and said pressure-foot to one another at the moment of cutting, substantially as set forth. 85

2. An arrangement as specified in claim 1, in which said counter-cutter and said pressure-foot are yieldingly arranged, substantially as set forth. 95

3. In an arrangement as specified in claim 1, a casing for the reception of said cut-off device and mounted to yield in a vertical 100 direction between said feed-gear, substantially as set forth.

4. In an arrangement as specified in claim 1, a casing for the reception of said cut-off device and mounted to yield in a vertical direction between said feed-gear, and means to impart to said pressure-foot and to said casing an additional tension at the moment when said cutter arrives at its cutting position, substantially as set forth. 105

5. An arrangement as specified in claim 1, in which said pressure-foot is at its end divided into two members with wedge-shaped extremities engaging over said counter-cutter, substantially as set forth. 110

6. An arrangement as specified in claim 1, in which said counter-cutter is of arched formation, substantially as set forth. 115

7. In an arrangement as specified in claim 1, a casing for the reception of said cut-off device mounted to yield in a vertical direction between said feed-gear, and a shaft for said cutter mounted in said casing and adjustable with reference to said counter-cutter, substantially as set forth. 120

8. In an arrangement as specified in claim 1, a casing for the reception of said cut-off device mounted to yield in a vertical direction between said feed-gear, and consisting of an outer sleeve and an inner sleeve yield- 125

ingly and adjustably mounted in the latter, and a shaft for said cutter mounted in said inner sleeve, substantially as set forth.

9. In an arrangement as specified in claim 1, guide-pieces at the front end of said cutter, substantially as set forth.

10. In an arrangement as specified in claim

1, guide-arms at the front end of said counter-cutter and laterally bounding the cutting-edge of the latter, substantially as set forth. 10

In testimony whereof I have hereunto set my hand.

HERMANN CHRISTIAN FISCHER.
